CLAIM

The ornamental design for a toy stacking clown, as shown and described.

DESCRIPTION

FIG. 1 is a front perspective view of a toy stacking clown showing my new design.

FIG. 2 is an exploded rear perspective view thereof.

FIG. 3 is a top plan view thereof.

FIG. 4 is a bottom plan view thereof.

FIG. 5 is a front elevational view thereof.

FIG. 6 is a side elevational view thereof; the rear elevational view and the opposite side elevational view being a mirror image.

FIG. 7 is a cross-sectional view taken along line 7-7 of FIG. 5.

FIG. 1

FIG. 3

FIG. 4

FIG. 6
